United States Patent Office

Des. 211,835
Patented July 30, 1968

211,835

CASING FOR A PRINTING MACHINE OR THE LIKE

Robert K. Yagura, Palo Alto, Calif., and Terry L. Barner,
Orange, N.J., assignors to Monroe International Corporation,
Orange, N.J., a corporation of Delaware

Filed Feb. 28, 1967, Ser. No. 5,982

Term of patent 14 years

(Cl. D64—11)

FIG. 3

FIG. 1 is a perspective view showing the front and left side of the case.

FIG. 2 is a right side elevation thereof.

FIG. 3 is a top plan view.

FIG. 4 is a front elevation.

FIG. 5 is a rear elevation.

The broken line disclosure of the base portion and printer mechanism are shown for illustrative purposes only to show the environment in which the case is used.

We claim:

The ornamental design for a casing for a printing machine or the like, as shown and described.
